CLAIM

The ornamental design for a baby car seat cover, as shown and described.

DESCRIPTION

FIG. 1 is a top, front and right side perspective view of a baby car seat cover, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the baby car seat cover with its zippers shown pulled down; and,

FIG. 10 is an enlarged view of portion 10 in FIG. 5.

The dotted broken lines shown on the baby car seat cover depict the features and stitching that form no part of the claimed design. The dash-dot-dash broken lines define the boundary of an enlarged view and form no part of the claimed design.
